Inventor:

UNITED STATES PATENT OFFICE.

RALPH G. SANDES, OF CHICAGO, ILLINOIS.

IMPROVEMENT IN ANCHOR-TRIPPERS.

Specification forming part of Letters Patent No. **179,731**, dated July 11, 1876; application filed March 3, 1875.

To all whom it may concern:

Be it known that I, RALPH G. SANDES, of the city of Chicago, in the county of Cook and State of Illinois, have invented a new and useful Improvement in Ship-Building, of which the following is a specification:

This invention relates to a new and important device for safely and expeditiously dropping the anchor of a ship or other craft or vessel carrying an anchor; and consists in the device of the double bolt, and in the combination and adaptation thereof with and to the catches and connecting-chains, as herein-after described.

The accompanying drawing represents a horizontal view of my invention as permanently attached to the rail and cat-head of a ship.

Similar letters of reference indicate corresponding parts.

A A is a metal bolt, shooting double. B is a metal plate, fixed permanently to the rail and cat-head, upon which plate the double bolt is fixed and slides. C is the rail, and D is the cat-head, of the ship. E is a catch, attached to the end of the ring-stopper K. F is a catch, attached to the end of the shank-painter L. These catches E and F are links sufficiently elongated to pass up through suitable ways cut through the rail and cat-head, respectively, and through the bolt-plate, and when the ends of the double bolt are shot through them, respectively, they are so held in place, and, in connection with the ring-stopper K and the shank-painter L, hold the anchor in position, clear of the rail, as represented by I. G is a knob on the bolt A A, so

placed that it acts as a stopper against one of the clasps that hold the bolt to the plate B. H is a pin, that holds the double bolt A A in place when shot through the catches E and F.

When the anchor is to be dropped from its position clear of the rail, this pin H is withdrawn, and then the respective ends of the double bolt are withdrawn from the catches E and F at once and together, by a blow of a maul on the knob G, sufficient to move the bolt, so that its ends are driven from and release the catches, and the catches E and F, being so released, pass instantly and simultaneously through their respective ways in the rail and cat-head, and the anchor, being thus at the same instant freed from the ring-stopper K and the shank-painter L, drops instantly, in a nearly horizontal position, into the water, free (except of its chain or cable) and without a possibility of fouling.

Having thus described my invention, I claim as new and desire to secure by Letters Patent—

The combination, with the rail C and cat-head D, each provided with a mortise to admit the catches E and F of the anchor-supporting chains, of the double bolt A A, provided with the knob G, and secured to the plates B B, so as to admit of a longitudinal movement, whereby the ends of said bolts are adjusted within the said catches or disengaged therefrom, substantially as specified.

RALPH G. SANDES.
